UNITED STATES PATENT OFFICE.

WILLIAM KANE, OF PHILADELPHIA, PENNSYLVANIA

HEATING APPARATUS.

No. 823,686.

Specification of Letters Patent.

Patented June 19, 1906.

Application filed February 11, 1905. Serial No. 245,253.

To all whom it may concern:

Be it known that I, WILLIAM KANE, of the city and county of Philadelphia and State of Pennsylvania, have invented an Improvement in Heating Apparatus, of which the following is a specification.

It is the object of this invention to provide a simple unitary independent heating apparatus constituting in itself a complete local heating system particularly adapted for use with gaseous fuel.

My improvements relate in part to the construction of the radiator whereby simplicity of construction is coupled with facility of erection and access to the circulating-tubes may be easily obtained for the purpose of cleaning or making repairs. To this end I employ a series of exposed massed vertical tubes with their upper and lower ends opening through and secured in apertures in horizontal plates, thus forming of said tubes and plates a united structure. To the upper plate is secured a crown-cap forming an extended air-space extending over the open tops of the tubes, and to the lower plate is secured a recessed base-frame forming a water-space extending below and communicating with the open lower ends of the tubes. This crown-cap and the base-frame are detachable, so that by removing them access may be had to the tubes. This radiator structure may be used either with a hot-water heater or with a steam-generator and will form with such heater or generator a complete local heating apparatus.

It is also one of the objects of my invention to dispense entirely with the expansion-tank which is usually employed in hot-water heating systems and to utilize in lieu thereof the air-space formed by the crown-cap of the radiator, which may be made open to the atmosphere. This omission of the expansion-tank not only simplifies the construction, but it renders the radiator more sightly. Another advantage of using an open crown-cap is that the moisture which passes off into the air improves the quality of the atmosphere, and this is of particular value in greenhouse-heating.

The base-frame constitutes the boiler or generator and is made sufficiently large to contain a longitudinal heating-flue extending through it, to which heat may be supplied in any suitable manner, preferably by a gas-pipe within the flue.

In the drawings, Figure 1 is a view, partly

in side elevation and partly in vertical section, of a heating apparatus embodying the invention; and Fig. 2 is a transverse vertical section of the same on the line D D of Fig. 1.

The body of the radiator consists of a series of massed and exposed vertical tubes *a*, secured at their ends in apertures in horizontal plates *b c*, preferably by the expansion of the tube-rims about said apertures.

d is a crown-cap of slightly dome shape which fits upon the upper plate *b* and is secured thereto at the edges by bolts *e*. *f* is a base-frame also dome-shaped or recessed similarly and is secured to the lower face of the base-plate *c* by bolts *e'*.

The faces between the plates *b* and *c* and the cap *d* and frame *f* may be suitably packed.

In assembling the radiator the tubes *a* are secured at their ends in the plates *b* and *c*, thus forming a united structure composed of a massed series of exposed vertical radiating and circulating tubes extending between the two horizontal plates to which the cap *d* and base *f* are secured.

Not only is this construction very simple and easily erected, but the use of a separate crown-cap and base-frame permits the expansion of the tube ends in the apertures of the plates, and the removability of the crown cap and base permits of access to the tubes and enables any tube to be removed and replaced without disconnecting other tubes.

The crown-cap *d* is also provided with an outlet *g*, fitted with a petcock *h*, and is open to the atmosphere. A thermometer *m* may be placed in an aperture in the top.

The radiator may be filled by removing the thermometer and pouring water into the upper chamber until the radiator is filled to the proper level. When the radiator is used for hot-water heating, the water should extend in the top chamber over the tops of the tubes *a*, leaving an extended air-space under the crown, which is open to the atmosphere through the aperture in which the thermometer fits loosely or through other apertures which may be provided.

The base-frame *f* is enlarged, and through it extends a longitudinal flue *t*, within which is arranged a longitudinal gas-burner *w'*. The ends of the flue *t* are open, and in the construction shown the burner is supported by spiders *w*, clamped to the open ends of the flue by the burner-chamber *w*² and the nut *w*⁴, screwed upon the ends of the gas-pipe.

In using this construction as a steam-gen-

erator only the base is filled with water, and the steam generated by the heat from the burner w' in the flue t' will pass up through the tubes a to the crown, while the water of condensation will return through the tubes back to the generating-chamber to be reconverted into steam. The moisture which passes off through the open crown-cap imparts a soft balmy quality to the air in the apartment very closely resembling the natural open summer atmosphere, and this quality renders the heater particularly effective for hothouse-heating. When used as a steam-radiator, the vent in the crown may be closed. Sufficient water should be added daily to compensate for the loss due to evaporation and to maintain the proper water-level whether the radiator be used as a steam or hot-water apparatus. In either case the apparatus is entirely independent and constitutes in itself a complete local heating system.

What I claim as new, and desire to secure by Letters Patent, is as follows:

1. A unitary independent heating apparatus, consisting of a series of exposed massed vertical tubes, a horizontal plate provided with apertures through which the lower ends of said tubes open and in which said ends are secured, a base-frame detachably secured to

the lower face of said horizontal plate and forming a water-space extending below and communicating with the lower open ends of said tubes, a heating-flue extending longitudinally below the horizontal plate through said water-space, and a crown extending over the upper open ends of the tubes. 35

2. A unitary independent heating apparatus, consisting of a series of exposed massed vertical tubes, a horizontal plate provided with apertures through which the lower ends of said tubes open and in which said ends are secured, a base-plate detachably secured to the lower face of said horizontal plate and forming a water-space extending below and communicating with the lower open ends of said tubes, a heating-flue extending longitudinally below said detachable horizontal plate through said water-space and open at its ends, a gas-burner extending longitudinally through said heating-flue, and a crown extending over the upper open ends of the tubes. 45 50

In testimony of which invention I hereunto set my hand.

WILLIAM KANE.
